UNITED STATES PATENT OFFICE.

RUSSELL H. MAXWELL, OF TRENTON, NEW JERSEY.

SHIP-PROTECTOR.

1,278,970.

Specification of Letters Patent. Patented Sept. 17, 1918.

Application filed November 8, 1917. Serial No. 200,930.

To all whom it may concern:

Be it known that I, RUSSELL H. MAXWELL, a citizen of the United States, and a resident of the city of Trenton and county of Mercer and State of New Jersey, have invented certain new and useful Improvements in Ship-Protectors, of which the following is a specification.

This invention relates broadly to devices 10 for protecting ships, and more particularly to devices of this nature adapted to be carried by the side of a vessel and swung to operative position at will to guard against destruction of the vessel by torpedoes. 15 The principal object of the present invention is to provide a device of this nature which may be readily swung from inoperative to operative position, and which when in operative position will protect the entire 20 side of the vessel from the water line to the keel.

A further object of the present invention is to provide a protector in the form of an outrigging adapted to normally occupy but 25 little space so as to offer comparatively small resistance to passage through the water.

A still further object of the present invention is to provide a protecting device in the form of a plurality of bars spaced apart 30 so that the water may readily pass between the same thereby relieving the device to a large extent from the impact of heavy seas.

Still another object of the present invention is to construct a protecting device of 35 two members wherein one of the members acts as a trigger operating means for the other member.

A still further and important object of the invention is to provide a protecting device 40 of the present character with members adapted to normally occupy inoperative positions, and constructed to be automatically swung to operative positions in which they will effectively bar the passage of a tor- 45 pedo.

A still further object of the invention is to provide a protecting device in the form of an outrigging which may be easily folded to inoperative position so that the same shall 50 occupy a minimum space.

A still further and important object of this invention is to construct the protector of a series of sections so that the destruction of one or more of the sections does not

necessitate the repair of the entire structure, 55 thereby reducing the cost of upkeep to a minimum.

The foregoing and other objects of the invention, together with their attendant advantages, will be apparent as the invention 60 becomes better understood by reference to the following specification, and drawings forming a part thereof, throughout the several views of which like characters of reference have been used to indicate like parts. 65

It has heretofore been old to provide vessels with solid sheets of protecting material adapted to be supported at the desired distance from the side of a vessel so as to intercept the passage of a torpedo. Devices 70 of this general nature have been objectionable for the reason that they interfere with the free motion of the water when the vessel is traveling in a heavy sea and thereby act to a certain extent as break-waters which 75 must sustain substantially the entire impact of the waves. If a protector of this type is constructed with sufficient rigidity to withstand such impact, it in turn transmits the same to the vessel so that the progress of 80 the same is impeded. On the other hand such devices are also objectionable for the reason that they interfere with the free travel of the vessel through the water due both to their weight and to the skin resist- 85 ance offered by reason of the large surface presented.

A modification of protectors such as before referred to has been contemplated in which the protecting member comprises 90 nets, cables or the like. While such constructions eliminate to a large extent the objections existing in connection with solid protectors, they have possessed such a degree of flexibility that they tended to interfere 95 with the free roll of the vessel, and they have not presented sufficient protecting surface to intercept the passage of all torpedoes.

With the present invention the difficulties before referred to are to a large extent over- 100 come. I have provided a protecting device in the form of an outrigging presenting comparatively little surface to bar the free motion of the water, or to retard the progress of the vessel through the water. At 105 the same time the protector is so constructed that the effective protecting surface is automatically increased by a torpedo upon its

approach, so that its passage to the ship is successfully blocked.

Realizing that my invention may assume different structural embodiments within the scope of the appended claims, I desire the drawings to be considered as illustrative of the preferred form of my invention, rather than in a limiting sense.

Referring to the drawings, Figure 1 is a sectional view of a vessel having my protecting device applied thereto.

Fig. 2 is a side view of a portion of said vessel showing the sectional arrangement of the protecting device.

Fig. 3 is an enlarged detail view of a part of the inner and outer protectors.

Fig. 4 is an end view of the construction shown in Fig. 3.

Fig. 5 is a sectional view on the line 5—5 of Fig. 4.

Fig. 6 is an enlarged detail view of a form of rod support for the outer protectors.

Fig. 7 is an enlarged detail view of the torpedo intercepting blades.

Fig. 8 is a sectional view on the line 8—8 of Fig. 7.

Fig. 9 is a longitudinal sectional view on the line 9—9 of Fig. 7.

Fig. 10 is a detail view showing a method of pivotally connecting the boom sections.

Fig. 11 is an enlarged detail view of a sliding brace employed.

Fig. 12 is an enlarged detail view partly in section of one of the supporting carriages for the protectors.

Referring more particularly to the drawings, I have illustrated a ship 1 of any desired construction in position for unloading on a dock 2. For preventing the vessel from approaching the dock closely enough to injure the protecting device, there may be provided a row of piling 4 spaced a suitable distance from the dock and adapted to act as a stop maintaining the vessel at all times a predetermined distance from the dock.

The protecting device herein shown preferably comprises a plurality of sections S, each section being composed of an inner protector 5 and an outer protector 6, both of which are supported by carriages 7 having anti-friction wheels 8 adapted to travel on the track-ways 9 formed on the supporting booms 10 projecting outwardly from the side of the vessel and constituting an outrigging for maintaining the protecting device in spaced relation to the side of the vessel. In its preferred form, each boom comprises an inner section 11, and an outer section 12 pivotally connected at 14 as shown more particularly in Fig. 10. The inner end of each of the booms has a pivotal connection 15 with the piston members 16 closely fitting within the chambers 17 having buffer springs 18 mounted therein to

absorb shocks transmitted to the booms through the protectors, or otherwise.

For raising and lowering the booms, and their associated parts, for placing the protectors in inoperative or operative positions as may be desired, I have shown a suitable type of windlass 19 secured at any convenient point on the vessel and adapted to wind up the cables 20 upon actuation thereof in the proper direction either manually or mechanically as desired. Any suitable and well known type of pawl and ratchet construction 21 may be used for preventing accidental rotation thereof in the wrong direction. The cables 20 are preferably connected to the outer ends of the inner boom sections 11 so that during the raising or lowering operation folding movement of the boom sections is freely permitted. Any suitable type of braces 22 may be employed at such positions as may be deemed most effective for rigidly maintaining the parts in operative position. As illustrated, the braces are pivotally connected at one end so that they swing about fixed axes, while at the other end they are pivoted to T-plates 24 adapted to slide in channel members 25 as shown in detail in Fig. 11. Since the mountings of all the various braces employed are the same, it is believed to be unnecessary to specifically describe each one separately. It will be understood that the general structure and arrangement of braces is such that they do not interfere with the movement of the booms from one position to another. In folding, the longer braces 22 are slid inwardly along their respective booms, whereby the inner pivoted portions of the braces may be slid upwardly out of engagement with the channel guides 25 on the sides of the vessel, and the entire structure folded along the booms in compact relationship therewith. Suitable cables 26 passing around fixed pulleys 27 may be employed for holding the braces in operative bracing positions.

It is believed that in view of the foregoing the construction and operation of the supporting booms will be readily understood. Mounted for travel in each of the supporting booms, in the manner heretofore briefly described, are carriages 7, a separate carriage being provided for each of the side bars 28 of each of the inner and outer protector members. Mounted on opposite sides of the bars 28 are angle iron braces 29 so positioned as to underlie the track-ways 9 and prevent undue swinging movement of the protectors. The angle irons 29 co-operate with the stops 30 thereby properly positioning the protectors as will be more fully pointed out hereinafter.

For moving or sliding the protectors along the track-ways there may be provided cables 31 passing around pulleys 32 on the ends of the booms, and connected in any desired manner to the outer protectors. The outer

protectors are in turn connected to the inner protectors 5 by means of flexible braces 34 tending to maintain the protectors in predetermined spaced relation, the limit of travel of the inner protectors 5 being determined by suitable stay wires or the like 35. Travel of the protectors in the opposite direction is obtained by means of the cables 36 passing around fixed pulleys 37 on the 10 booms and secured to the opposite side of the outer protectors. Buffers 38 positioned at desired intervals on either of the protectors are provided for maintaining the same in proper spaced relation when moved 15 to inoperative position for folding.

Each of the protectors is preferably constructed of upper members 39 pivotally secured to the carriages 7 by any form of pivot permitting movement through an arc 20 of 90°, and lower members 40 pivotally secured to the ends of off-set portions 41 on the upper members. By reference to Fig. 1 it will be seen that the pivotal connections for the inner and outer members are in different vertical planes thereby permitting the same to nest as shown in dotted lines until the buffers become effective to limit the movement thereof. From nested position the lower ends of the protectors may be swung 25 upwardly, as shown, by means of cables 42, so that the entire device may be compactly folded to inoperative position so as not to interfere to any great extent with the loading and unloading of the vessel. The construction of the protectors whereby the lower 30 members of the same constitute pivoted continuations of the upper members but extending in a different plane is an important feature of the present invention, inasmuch as it permits folding or unfolding of the 35 protectors while projected below the water line.

Both members of each of the inner protectors are provided with a series of transverse bars 44 rigidly secured to the side bars 28 in spaced relation as clearly shown in Fig. 3. The length of the bars 44 may be varied within wide limits in accordance with the number of sections of which the 40 protecting device is constructed. Each of the bars 44 has pivotally mounted on opposite sides similarly constructed torpedo intercepting blades 45. In order that the weight of the entire device may be decreased 45 to a minimum, and also in order that the bars and blades may present as little surface as possible to the medium through which the same is traveling, the blades are preferably constructed with inclined sides 46. 50 In normal inoperative position the blades 45 are adapted to extend in substantial parallelism with the supporting bars 44 as shown clearly in Fig. 7. The blades are maintained in this position by catches or triggers 47 55 adapted to engage notches 48 formed in the

ends of the blades. The triggers are held in engaging position by springs 49 mounted in housings 50 against which they abut. Tending to move the blades 45 around their pivots 51 are springs 52 having tension coils 54 secured in any desired manner to the bars 44. The ends of the springs are mounted in keepers 55 projecting from the sides of the blades. It will be apparent that upon release of the triggers the springs will be effective to swing the blades, swinging movement being limited by the transverse stops 56 mounted on the bars 44. The stops 56 are preferably so positioned that they maintain the blades, while in open or operative position, at substantially right angles to the supporting bars. 60

Since an object of the present invention is to decrease to as large an extent as possible the surface presented at all times so that the free motion of the water is not prevented to any large extent, it is preferred to space the bars 44 such a distance that there would be room between the same for the passage of a torpedo if the arms 45 were in their inoperative positions in parallelism with the supporting bars. For effectively preventing the passage of a torpedo, it becomes necessary, therefore, to provide trigger actuating mechanism for the triggers 47 so that upon the approach of a torpedo the intercepting blades 45 will be swung to operative positions. For functioning in this manner I have provided the outer protectors 6 with flexible strips or bars 57 of any desired shape and constructed of any suitable comparatively flexible material, such for example as chrome nickel steel. The rods 57 are mounted in eye-bolts 58 or the like extending through the side bars 28 which may be round or rectangular in shape, and yieldingly supported to permit a limited lateral movement thereof by springs 59 surrounding the same and abutting at one end against the bars 28 and at the other end against collars or cross pins 60. The rods 57 are of such length that they project to a considerable extent beyond the sides of the bars 28. It is contemplated that the rods shall have sufficient flexibility so that upon being struck by a moving object traveling in the direction of the arrow in Fig. 5 the same shall be bent inwardly to dotted line position, thereby moving the ends outwardly away from the supporting bars. This movement of the ends of the rods is relied upon for actuation of the triggers 47 through the following connecting mechanism: Each of the triggers has a projecting handle or knob 61 adapted to receive or have secured thereto a cord 62 extending the length of the bars 44 so as to be connected to each of the triggers. The cords 62 are in turn connected to cords or the like 64 passing through suitable guides 65

65 on the side bars 28 of the inner protectors. The cords 62 and 64 are then joined to the ends of the rods 57 by suitable tension members 65'. It will be understood that in
 5 case the blades are all mounted for movement in the same direction, that it will be necessary to only provide tension members 65' at one end of the rods 67. Since, however, the arrangement of the blades may be such that
 10 a movement of the triggers in the opposite direction from that shown is required for their release, I have in Fig. 3 illustrated the possibility of providing suitable tension members secured to opposite ends of the
 15 rods.

It is believed that from the foregoing the construction and operation of my protecting device will be obvious. By reason of the boom construction, the entire device may
 20 be lifted above the water line when the vessel is traveling through neutral waters, and then lowered as the same approaches a danger zone. The arrangement of protectors permits a compact folding of the same
 25 when in inoperative position, and the provision of inner and outer protectors is desirable as the outer protector may then function as a trigger actuating means for the inner protector, thereby decreasing the number
 30 of parts which would ordinarily be necessary to successfully intercept the passage of a torpedo. At the same time, by reason of this construction the device normally presents a comparatively small
 35 surface area to the medium through which it is traveling, which area is automatically increased by and upon the approach of a torpedo.

Inasmuch as it is expected that a single
 40 torpedo may destroy one or more sections of the protecting device, there may be provided for use in connection with this construction a net which may be rolled down the cables 31 and weighted to assume a position
 45 in front of the section of the protector which has been destroyed. This will act to temporarily repair the entire device until the section or sections destroyed can be replaced.

50 What I claim is:—

1. A protecting device for vessels, comprising a plurality of bars, blades mounted thereon, and means for changing the position of said blades upon the approach of
 55 a torpedo.

2. A sectional protecting device for vessels, comprising a plurality of bars, torpedo intercepting blades mounted thereon, and means for changing the position of said
 60 blades upon the approach of a torpedo.

3. A protecting device for vessels, comprising a plurality of bars, torpedo intercepting blades mounted thereon, and means for automatically changing the position of
 65 said blades upon the approach of a torpedo.

4. A protecting device for vessels, comprising a plurality of bars, torpedo intercepting blades mounted thereon and normally maintained in inoperative position, and means for moving said blades to operative position upon the approach of a torpedo.
 70

5. A protecting device for vessels, comprising a plurality of bars, spring pressed torpedo intercepting blades mounted thereon, and means actuated by a torpedo for
 75 automatically moving the said blades to torpedo intercepting position.

6. A protecting device for vessels, comprising a plurality of bars, torpedo intercepting blades carried thereby in inoperative position, means for maintaining said blades in inoperative position, and means for automatically moving said blades to operative position upon the approach of a torpedo.
 80

7. A protecting device for vessels, comprising a plurality of bars, blades pivotally mounted thereon, a catch for holding said blades in inoperative position, and spring pressed means for moving the blades to operative position upon the release of said
 85 catch.
 90

8. A protecting device for vessels, comprising a plurality of bars, torpedo intercepting blades mounted thereon, means for holding said blades substantially parallel to said bars to decrease resistance of the same to travel through the water, and means for moving said blades to positions at substantially right angles to said bars to increase the effective protecting surface.
 95

9. A protecting device for vessels, comprising an inner protector, an outer protector, torpedo intercepting blades on the inner protector, and means on the outer protector for controlling the position of said blades.
 100

10. A protecting device for vessels, comprising an inner protector, an outer protector, torpedo intercepting blades on the inner protector normally occupying inoperative positions, and means on the outer protector for causing said blades to move to operative positions.
 110

11. A protecting device for vessels, comprising an upper member having an offset at its lower end, a lower member constituting a continuation thereof in a different plane, and means at the extremity of the offset for pivotally connecting said members.
 115

12. A protecting device for vessels, comprising an inner protector having an upper member provided with an offset at its lower end, a lower member constituting a continuation thereof in a different plane, means at the extremity of the offset for pivotally connecting said members, and an outer protector cooperating therewith.
 120

13. A protecting device for vessels, comprising an inner protector, an outer protector, each of said protectors comprising upper and lower members constituting continua-
 125
 130

tions of each other in different planes, and means for pivotally connecting said members.

14. A torpedo intercepting device, comprising a bar, a blade pivotally mounted on said bar, means for maintaining said blade normally in parallelism with said bar, and means for causing said blade to assume an angular relation to said bar.

10 15. A protecting device, comprising supporting booms, means for raising and lowering said booms, and inner and outer protector members carried thereby, the inner protector member being provided with a plurality of torpedo intercepting blades normally in inoperative positions, and the outer protector constituting a control for moving said blades to operative positions.

16. A protecting device, comprising sup-

porting booms, means for raising and lowering said booms, and inner and outer protector members pivotally carried thereby, the inner protector being provided with a plurality of torpedo intercepting blades normally in inoperative positions, and the outer 25 protector constituting a control for moving said blades to operative positions.

17. A protecting device, comprising supporting booms, means for raising and lowering said booms, and inner and outer protector members slidably and pivotally carried thereby, the inner protector being provided with a plurality of torpedo intercepting blades normally in inoperative positions, and the outer protector constituting a control 35 for moving said blades to operative positions.

RUSSELL H. MAXWELL.
